(57) CLAIM

The ornamental design for a “massage apparatus,” as shown and described.

DESCRIPTION

FIG. 1 is a bottom and right side perspective view of a massage apparatus according to my design;

FIG. 2 is a top and left side perspective view thereof;

FIG. 3 is a top plan view thereof;

FIG. 4 is a right side elevational view thereof, the left side elevation being a mirror image thereof;

FIG. 5 is a front elevational view thereof; and,

FIG. 6 is a rear elevational view thereof.
